UNITED STATES PATENT OFFICE.

JAMES A. HARVEY, OF BURLINGTON, VERMONT.

APPARATUS FOR FREEING GUTTERS, STREET-CROSSINGS, AND SIDEWALKS FROM ICE AND SNOW.

SPECIFICATION forming part of Letters Patent No. 245,490, dated August 9, 1881.

Application filed May 27, 1881. (No model.)

To all whom it may concern:

Be it known that I, JAMES A. HARVEY, of Burlington, in the county of Chittenden and State of Vermont, have invented certain new and useful Improvements in Apparatus for Freeing Gutters, Street-Crossings, and Sidewalks from Ice and Snow; and I do hereby declare the following to be a full, clear, and exact description of the invention, such as will enable others skilled in the art to which it pertains to make and use it, reference being had to the accompanying drawings, which form part of this specification.

My invention relates to an improved apparatus for freeing gutters, street-crossings, and sidewalks from ice and snow, the object being to accomplish such a result through the agency of devices combining simplicity of construction with efficiency and durability in use, and which are adapted to be maintained at a comparatively light expense.

With these objects in view my invention consists in certain details of construction and combinations of parts, as will be hereinafter described, and pointed out in the claims.

In the accompanying drawings, Figure 1 is a view in perspective, showing the application of my invention to a gutter, and also auxiliary appliances by means of which the steam in the main pipes may be employed in thawing out frozen hydrants and in removing masses of snow and ice beyond the influence of the radiated heat. Fig. 2 shows, in vertical cross-section, the application of my improved apparatus to a gutter and crossing. Fig. 3 is a view of one of the stools on which the pipes are supported in their trenches. Fig. 4 is a view in end elevation of one of the plates forming the upper wall of the gutter-trench. Fig. 5 is a side view thereof, and Fig. 6 is a view of one of the plates employed in street-crossings provided with my apparatus.

A represents a trench running parallel with the curb C of the sidewalk. The side walls, B B, and the floor D of the said trench may be of any suitable construction, provided only that the upper extremities of the walls B B are adapted to receive and support the gutter-plates E, and that the floor D is sufficiently level to offer firm bearing for the stools F. It is, however, advisable, and the apparatus will give more perfect satisfaction if the walls and

floor of the trench are practically air-tight, as it is desirable from economical reasons that the gutter-plates shall be heated to the highest possible degree with the waste of the least possible amount of heat. The top of the trench, which, in fact, forms the gutter, is made up of a series of slightly-concaved iron plates, E, the edges of which rest on the upper extremities of the walls. The ends of said plates are adapted to lap over one another in such manner as to constitute a continuous trough. These plates are capable of being individually removed, when it becomes necessary to obtain access to the interior of the trench, with the outlay of little trouble and without disturbing the rest of their number.

Pipes G of varying diameter, as may be required, and connected with a suitable steam-supply, are supported centrally of the trenches upon stools F, which are of different heights, and arranged with reference to the deflection which it is desired to impart to the pipe to cause the water produced by the condensation of steam therein to be collected, and to discharge the same into a sewer or other outlet.

In Fig. 2 of the drawings is shown one of the devices employed for emptying water into the sewer. Said devices consist in a pipe, H, having communication with a section of the main pipe, and terminating at its lower end in a valve-chamber, I, in which is located a float-valve, J, actuated in rising and falling movement by a hollow ball, K. When the valve J is lifted from its valve-seat L open communication is established between the pipe G and a sewer or other outlet. The operation of this valve is very simple, and may be described as follows: The water formed by condensation of steam within the pipe will accumulate in sinking to its lowest level in the chamber I aforesaid. When it has accumulated therein in sufficient quantities to float the ball K the valve will be opened and the water will be discharged into the sewer. Before the water has been entirely discharged the ball will cease to be floated, the valve will be closed, and the escape of steam thus prevented. These emptying devices described above, or their equivalents, are situated at every deflection of the main pipe to discharge the water collected at such point and permit the unimpeded passage of the steam. M represents a supply-pipe leading to the

main pipe G, and N represents a pipe extending under the crossing to keep it dry and clear from ice and snow. The trench for a crossing should be built on the same principle as that upon which the gutter-trenches are reconstructed, save only that the plates P should have a flat and preferably roughened surface. As to the sidewalks, the pipes may traverse them laterally or longitudinally as may be deemed most expedient.

At or near every hydrant A³, I contemplate the arrangement of devices whereby a portion of steam from the pipe G may be conducted to them to thaw them out in case of freezing. This I accomplish by providing a section of the main pipe G with a hose attachment, A², to which a hose, B', may be secured.

By inserting the free end of the hose into an orifice in the hydrant and turning on the steam through valve B², I am enabled to quickly thaw out the hydrant. Again, by providing hose of suitable lengths I am enabled to direct jets of steam onto and melt masses of ice and snow located beyond the influence of the heat radiated from the pipes. The steam may be derived from any suitable source, and may be generated especially for the apparatus, or exhaust-steam from steam-heated buildings and factories along the line of pipes may be conducted thereto and answer all the objects of invention. A high degree of heat for the plates is not desired, as it will be sufficient to keep them continuously heated above the freezing-point. If such a degree of heat is maintained, the accumulation of ice and snow in the gutter may be at all times avoided.

From the description hereinabove given the simplicity of construction of the apparatus and the slight attention it demands are very apparent. It requires comparatively little steam, and in most instances that can be obtained without the expense of running especial generating apparatus.

I would have it understood that I do not limit myself to the exact construction shown and described, but hold myself at liberty to make such slight changes and alterations as fairly fall within the spirit and scope of my invention.

I am aware that it is not new to locate heating-pipes beneath sidewalks, streets, and gutters, the pipes being embedded in the earth, and hence I make no claim to such a system of heating. My improvement differs from the system of heating referred to in that I employ open trenches which are covered by metallic gutters, the heating-pipes being located in the open trenches in close proximity to the under surface of the metallic gutters.

Having fully described my invention, what I claim as new, and desire to secure by Letters Patent, is—

1. The combination, with a metallic gutter, of heating-pipes located in a trench formed beneath the gutter, substantially as set forth. 65

2. The combination, with a gutter composed of metal plates formed with overlapping ends, of heating-pipes located in a trench formed beneath the gutter, substantially as set forth.

3. The combination, with a metal street-crossing, of heating-pipes located in a trench formed underneath said street-crossing, substantially as set forth. 70

4. The combination, with a street-crossing composed of metal plates formed with overlapping ends, of heating-pipes located in a trench formed beneath the street-crossing, substantially as set forth. 75

5. The combination, with gutters and street-crossing formed of removable metal plates, of heating-pipes located in trenches formed beneath said plates, and a series of stools graduated in height and arranged to support the heating-pipe at any angle of inclination, substantially as set forth. 80

6. The combination, with a series of steam-pipes for heating gutters, street-crossings, or sidewalks, of pipe-supporting stools arranged to support the pipes at any desired angle of inclination, and devices connected with the lowest points of the steam-pipes for automatically discharging the water of condensation, substantially as set forth. 85

7. The combination, with a system of steam-pipes for heating gutters, street-crossings, and sidewalks, of valve-chambers located beneath said pipes and provided with conduits communicating therewith, and float-valves located within the valve-chambers and adapted to automatically discharge the water of condensation without permitting the escape of steam, substantially as set forth. 95

8. The combination, with metal gutters and steam-pipes located in trenches formed beneath said gutters, of a hose-coupling for the attachment of a hose to convey steam to a hydrant or other point or object, substantially as set forth. 100

In testimony that I claim the foregoing I have hereunto set my hand this 21st day of May, 1881. 110

JAMES A. HARVEY.
